Des. 194,744
Patented Mar. 5, 1963

194,744

LABORATORY BEAKER

Joseph M. Pezely, Jr., New York, N.Y., assignor to Corning Glass Works, Corning, N.Y., a corporation of New York

Filed Dec. 19, 1961, Ser. No. 67,979

Term of patent 14 years

(Cl. D16—1)

Fig. 1

Fig. 2

FIG. 1 is a top view of a laboratory beaker embodying the design.

FIG. 2 is a side elevational view thereof.

The undisclosed side is a mirror image of the side shown, and the bottom is substantially flat and plain.

I claim:

The ornamental design for a laboratory beaker, as shown and described.
